UNITED STATES PATENT OFFICE

JOSEPH S. MALIK, OF CLEVELAND, OHIO

DESIGN FOR A FLOWER STAND

Application filed March 15, 1932. Serial No. 43,201. Term of patent 7 years.

To all whom it may concern:

Be it known that I, JOSEPH S. MALIK, a citizen of the United States, residing in Cleveland, in the county of Cuyahoga and State of Ohio, have invented a new, original, and ornamental Design for a Flower Stand, of which the following is a specification, reference being had to the accompanying drawing, forming part thereof.

The figure is a perspective view of a flower stand, showing my new design.

I claim:

The ornamental design for a flower stand, substantially as shown.

Signed by me this 11th day of March, 1932.
JOSEPH S. MALIK.
